G. MICHT.
SCUTCHING OF FLAX AND OTHER FIBROUS MATERIALS.
APPLICATION FILED MAY 21, 1918.

1,304,791.

Patented May 27, 1919.

Attorney.

UNITED STATES PATENT OFFICE.

GEORGES MICHOT, OF DROMARA, IRELAND, ASSIGNOR TO FIBRE CORPORATION
LIMITED, OF LONDON, ENGLAND.

SCUTCHING OF FLAX AND OTHER FIBROUS MATERIALS.

1,304,791.

Specification of Letters Patent. Patented May 27, 1919.

Application filed May 21, 1918. Serial No. 235,791.

To all whom it may concern:

Be it known that I, GEORGES MICHOT, a citizen of the Swiss Republic, and residing at Dromara, county Down, Ireland, have 5 invented certain new and useful Improvements in and Relating to the Scutching of Flax and other Fibrous Materials, of which the following is a specification.

This invention relates to the scutching of 10 flax and other fibrous materials, and more particularly to machines in which the fibrous materials are inserted between a band and a drum or pulley around which the band is adapted to travel, so that as the drum rotates 15 the material is gripped and carried around a circumferential path while being subjected to the action of one or more conveniently disposed scutching devices as described in my prior application Serial No. 20 186199, filed August 14, 1917.

The present invention is directed to the production of an improved scutching machine of the above indicated type.

The invention consists in arranging a 25 group of four scutching heads, each with its appropriate scutching wheel, in pairs one above the other, the blades of which can be arranged either in pairs as shown, or singly, to operate in the latter case alternatively on 30 either side of the machine, the bundles for scutching being operated on at all four heads one after the other.

The invention further consists in providing 35 an intermittent feeding device serving all four heads, and in various other features of construction.

In the accompanying drawings and description the invention is more fully explained, in which:—

40 Figure 1 shows a front elevation as arranged with four scutching heads and wheels in tiers with appropriate framework to support the upper tier.

Fig. 2 shows a cross-section of the above 45 taken through the line 2—2; and

Fig. 3 shows an end elevation of the complete machine.

In carrying this invention into effect in 50 the form shown, four scutching heads a , a' , a^2 , a^3 are provided in one machine, each of which is supported in bearings b , b' , b^2 , b^3 secured to vertical steel frames c , c' , supported on a suitable foundation and having cross beams c^3 for carrying the upper part 55 of the machine, the lower part being firmly secured to the foundation.

The scutching heads are arranged with the scutching points or zones at the corners of a rectangle in the order in which the scutching is effected, *i. e.*, the second head a' is arranged above the first head a and the third a^2 above the fourth a^3 .

The flax or the like fibrous material is conveyed through the scutching zones by being gripped between two endless narrow 65 flexible belts d , d' , mounted in a manner similar to those described in my prior application Serial No. 186199, filed August 14, 1917.

The bundles of fiber are placed in position at suitable intervals, as described in my prior application. The double belts d , d' carrying the bundles for scutching pass from the first scutching head a nearly vertically upward to the second scutching head a' on 70 the higher level, and means are provided for maintaining the bundles in their relative positions between the belts during this upward travel which consist of supporting fingers e' carried on an intermittently fed endless belt e or the like, mounted on pulleys f , f' supported above one another in the central part of the machine, and which are driven by bevel gearing g , g^2 from the axis of the feed wheel g at the same relative 75 speed as the feed belts d , d' . The projecting fingers e' on the belt e are U-shaped to engage the bundles and are spaced the proper distance apart to engage the bundles as they are fed by the main feed bands, and pass on 80 either side of the feed belts d , d' just below each bundle, coming into engagement therewith as the belts turn over the guide pulley h just above the first scutching head, and support the bundles in their upward course 85 until near guide pulley h' and next around the upper pulley j' after which they engage the bundles in their downward travel between the guide pulleys h^2 , h^3 ; the bundles then proceed around the last scutching head 90 a^3 and pass to the point where they become 95 released and then removed.

The operation of the machine is as follows:—

The flax straw is placed between the 105 bands d , d' at h projecting about six inches on the opposite side, for all lengths of straw, for example should the straw be three feet in length the overhanging portion on the scutching side, this is invariably the root end of the straw first to be operated upon and would be two feet four inches 110

long, plus two inches between the bands making with the short portion of straw on opposite side three feet in all. The bundles then proceed and come into contact with the 5 blades of the first scutching wheel *a* where they are roughed between the blade and vertical horn plate *l*, the bundles are next conveyed between the vertical bands *d*, *d'* assisted by the U-shaped projections on the 10 supplementary band *e* to the second scutching head *a'*, the bundles of straw are then subjected to the lateral changer, whereby its position in regard to the feed bands is altered so that the part of the material 15 gripped between the feed bands during its passage through the zone of the first and second scutchers will be operated upon by the next scutchers in the series, after which it reaches the delivery point from whence 20 it is removed by hand.

The flax or other fiber being treated is always shorter on one side, except with short lengths which are placed centrally, but this is not of frequent occurrence; two 25 feet is about the shortest straw on the average.

Having now described my invention, what I claim as new and desire to secure by Letters Patent is:—

30 1. A machine for scutching flax straw and other fibrous material comprising in a single machine two pairs of scutching wheels arranged in a vertical direction above each other, each wheel being provided with a 35 series of blades which are caused to operate

in sequence upon one or both ends of the bundles of straw fed into the machine in combination with central structures supported on foundations provided with vertical horn-like plates and guide pulleys for 40 feed bands, curved recesses for embracing the serrated edges of feed wheels, which latter are attached to guide pulleys supported in bearings in the central portions of each framework; a series of guide pulleys of 45 smaller diameter for guiding and supporting endless flexible bands, between which the fiber is gripped and carried by said bands from the point of insertion to the point of delivery; a centrally disposed intermittently operated feed wheel in the lower central part of framework around which the feed band is frictionally gripped; a centrally disposed pair of grooved wheels around the 50 surfaces of which is mounted an endless flexible band with U-shaped projections attached thereto in the upper portion of machine, independently operated at the same linear speed as the feed bands, substantially as described.

2. In a machine for scutching flax, straw and other fibrous material as claimed in claim 1, the combination of a lateral changing device placed mid-way in the process to cause a more effectual scutching effect to 55 be obtained in the manner described.

In testimony whereof I have signed my name to this specification.

G. MICHOT.
